STOKER FOR FURNACES

George A. Kohout, Chicago, Ill.

Application July 26, 1941, Serial No. 404,131

5 Claims. (Cl. 110—105)

The present invention relates to stokers for furnaces and more particularly to stokers of the type wherein coal is fed from a large hopper by a plurality of feed screws to the interior of the furnace and then sprayed by means of a fluid blast into the combustion chamber of the furnace. The construction is such that the coal is fed through individual housings by the feed screws to an inclined, expanding outlet at the furnace end of the screw housing. The coal then rolls down the inclines of the screw housings and is struck by an air stream which blows the coal dust and small particles away from the larger particles of coal. The air stream also gives an added impetus to the larger particles of coal so that these particles are sprayed out into the furnace and spread along the length of the grate according to the weight and size of each piece. The coal particles, when they pass downwardly through the air stream, strike a spreader plate and rebound so as to get the full effect of the air stream.

It is the principal purpose of this invention to provide improvements in the feed screw housings and the associated air delivery and spreader plate constructions whereby to cause a device of this character to function more efficiently over a wide range of coal capacity and to avoid difficulty due to coal packing or coking in the outlet of the screw housing.

More specifically it is a purpose of this invention to provide a fuel feeding unit embodying feed screws and feed screw housings wherein the housings are constructed to be substantially D-shaped in cross section throughout and beyond the length of the screw with an inclined outlet portion on each of the screw housings extending downwardly from the furnace end of the screw and toward the combustion chamber of the furnace at such an angle as to bring the upper edge of the outlet at the furnace end slightly above or at the level of the screw axis. The inclined outlet desirably is tapered or expanded toward the combustion chamber, thus providing adequate release of the coal to prevent it from coking and sticking in the outlet.

The invention contemplates a construction of screw and housing wherein the housing has interior dimensions substantially larger than the screw diameter and wherein the screw rests loosely on the floor of the housing so that large particles of coal, etc. that enter the housing can work along the top of the screw and be carried to the discharge end of the housing.

Other and more detailed objects and advantages of the invention will appear from the fol-

lowing description, reference being had to the accompanying drawings wherein a preferred form of the invention is shown. It is to be understood however that the drawings and description are illustrative only and are not to be taken as limiting the invention except insofar as it is limited by the claims.

In the drawings:

Fig. 1 is a view in front elevation of a furnace embodying the invention, the fuel hopper and the feed screw driving mechanism being cut away to illustrate the inlet to the feed screw housings;

Fig. 2 is a sectional view taken on the line 2—2 of Fig. 1;

Fig. 3 is a view taken substantially on the line 3—3 of Fig. 2 with certain parts broken away to illustrate the outlet ends of the feed screw housings;

Fig. 4 is a fragmentary sectional view taken substantially on the line 4—4 of Fig. 1;

Fig. 5 is a fragmentary plan sectional view taken substantially along the line 5—5 of Fig. 1, certain parts being left out for the sake of clearness;

Fig. 6 is a fragmentary perspective view of a portion of a feed screw housing embodied in the present invention;

Fig. 7 is a perspective view of a filler block which is utilized between adjacent housings for spacing them;

Fig. 8 is a perspective view of a plate which is utilized to support the inner ends of the air nozzles and to provide a shelf from which the coal fed to the furnace will rebound; and

Fig. 9 is a fragmentary sectional view through the inner or furnace end of a feed screw housing and its associated blast plate, this form being slightly modified in comparison with the main form of the invention.

Referring now in detail to the drawings, and particularly to Figs. 1 and 2, the present invention is embodied in a furnace having a combustion chamber 10 beneath which there are grates 11. The front of the furnace is illustrated in Fig. 1, the entire front being covered by a sheet metal plate 12. Overfire doors 13 and 14 are provided at the front of the furnace and ash pit doors 15 and 16 are located just below the overfire doors. At the left of the furnace as

shown in Fig. 1 there is provided a fan housing 17, the outlet 18 of which (see Fig. 2) opens into a spreading chamber 19 so as to supply air under pressure beneath the grates 11. A motor 20 drives a fan (not shown) in the fan housing 17. An air duct 21 extends across the front of

the furnace just above the doors 13 and 14. This air duct is fed from a fan housing 22 in which a fan 23 of the centrifugal type is mounted (see Fig. 4). A motor 24 drives the fan 23. This motor is suspended from the furnace by means of a bracket 25.

A coal hopper 26 is mounted at the front of the furnace. This hopper comprises a bottom portion made up of two channel irons 27 and 28 which extend across the front of the furnace, two end walls 29 and 30, and front panels 31, 32 and 33, the front panels and end walls being secured together in any suitable fashion. A coal agitator 34 is mounted in the hopper 26. The hopper also has therein a plurality of feed screws 35. There may be any desired number of feed screws, depending upon the width of the furnace. In the present instance I have shown four such feed screws. The feed screws are connected as shown best in Fig. 2 to drive shafts 36, which shafts are driven intermittently by a pawl 37 and a ratchet wheel 38. The details of the pawl and ratchet mechanism are shown more clearly in my prior Patent No. 2,178,360 of October 31, 1939. Since the present invention is not directed to any features of the drive mechanism the details thereof are not shown.

The coal agitators 34 have gear teeth 39 engaging the screws 35 so as to be driven when the screws are rotated.

The feed screws 35 extend from the hopper into feed screw housings 40. One end of each feed screw housing includes a plate 41 which extends over the channel irons 27 and 28 so as to be supported thereby. Connection is made between the feed screw housings and the front plate 12 of the furnace by means of a channel 42 on each housing (see Fig. 5) and a lock plate 43 that drops down into the channel in front of the plate 12, the plate 12 of course being provided with an aperture big enough to permit passage of flanges 44 and 45 on opposite sides of the channel 42. The housing 40 comprises a casting and the screw receiving passage 40a therein is substantially D-shaped in cross section as shown clearly in Fig. 6. This passage 40a is substantially larger than the screw diameter; for example, 5 inches horizontally and vertically for a 4 inch screw. The screw rests loosely on the floor of the passage. Large coal particles are thus caused to ride on the top of the screw and may pass through the housing without sticking and breaking the shear pins for the screw.

The inner or furnace end of the housing 40 includes a portion 46 substantially rectangular in cross section and below the feed screw opening. This rectangular hollow portion 46 is adapted to receive and support a blast plate 47 and a fluid nozzle 48. The fluid nozzle 48 extends through an opening 49 in the front furnace wall 12 and is connected to the air duct 21 through an opening 50 in the top of the air duct. Individually adjustable valves 51 are provided in the nozzles 48 so as to control the supply of air thereto. The passage 40a extends to the end of the feed screw 35 and from about the end of the feed screw it is directed angularly downward and is flared outwardly as indicated at 52. The top wall 53 of the outlet portion 52 extends downwardly at an angle of about 30° to the horizontal to a level slightly above the axis of the feed screw 35. The extreme bottom wall 54 of the outlet is directed downwardly at a slightly greater angle than the top wall 53. It is much shorter. The side walls 55 and 56 (see Figs. 3 and 5)

also flare outwardly toward the furnace combustion chamber so as to provide an expanding outlet from the end of the feed screw 35 to the combustion chamber. The fact that the outlet 52 expands and extends angularly downward into the combustion chamber prevents fuel from coking in front of the screw and enables the coal to roll freely from the front end of the screw down the inclined wall 54 across the outlet end of the nozzle 48 onto the plate 47.

The plate 47 is shown in perspective in Fig. 8. This plate has two rearwardly extending portions 57 and 58, which portions are provided with depending lugs 59 and 60 that are adapted to hook over the back of the part 46. At the front end the plate 47 has an enlarged portion 61 that extends down in front of the part 46. The portion 61 is provided with a plurality of channels 62 so that air may be fed by natural draft through these channels into the combustion chamber. The air of course enters from the front of the furnace through the openings 49 or it may be forced into the hollow space by a fan. Since the blast plate is subject to the heat of the furnace this air inlet provision is important in keeping the temperature of the blast plate down. However, it is a simple matter to replace a blast plate if it is damaged by heat or when it becomes worn by the action of the coal falling thereon and rebounding therefrom. It will be noted that the plate 47 has a flat top surface 64 and a steeply inclined front surface 65. The nozzles 48 direct their blast outwardly in a flaring stream across the surface 64. The flaring outlet of the nozzles 48 is shown best at 66 in Fig. 5 where it will be seen that this flaring outlet follows the flare of the walls 67 and 68 at the side edges of the surface 64.

The front furnace wall is constructed of the usual refractory materials and includes a bed plate 69 (see Fig. 2) and a refractory insulating wall 70 which serves to support the inner end of the several housings 40, the portions 46 of the housings resting directly upon the refractory wall 70. Above the housings 40 there is an air space 71 extending across the front of the furnace. This air space is adapted to receive air through a side opening 72 in the furnace. This air in fact may come from the air passages that are commonly provided in the side walls of furnaces for cooling the side walls. Above the air space 71 the refractory material indicated at 73 completes the front furnace wall. This upper refractory material is supported by an I-beam 74 and a metal plate 75.

In order to protect the inner ends of the housings 40 from the direct heat of the furnace I provide castings 76, which castings are adapted to fit on and be supported by an upwardly extending flange 77 on each of the housings 40. The castings 76 have flanges 78 upon which arch tile 79 is hung. The arch tile is slotted so as to receive the flanges 78. It will be noted from Fig. 3 that there are two flanges 78 on each casting 76. Each casting 76 has its top surface provided with a plurality of ribs 80 so as to form air passages across the top of the casting from the air chamber 71. Filler bricks 81 are placed on top of the ribs 80 and the space between the bricks 81 and the refractory material 73 is filled with a suitable plastic refractory indicated at 82.

Where the housings 40 are spaced apart I provide means for closing the space between the housings. This means comprises castings of the

type illustrated in perspective in Fig. 7. These castings 83 have top flanges 84 cooperating with the flanges 77 to support the castings 76. The castings 83 also have laterally extending lugs 85, 86, 87 and 88, which lugs are adapted to engage behind the flanges 77 at the sides of the inner ends of the housings 40. In order to aid in keeping the castings cool and in furnishing air for combustion purposes these castings preferably are provided with air passages 89 and 90. It is believed to be evident from an inspection of Figs. 3, 5, 6 and 7 how the castings 83 are interlocked with the housings 40.

Referring now to Fig. 9, in this form of the invention a slight modification has been made which in certain instances is desirable for the protection of the feed screws 35. This modification consists in providing a pivoted door 91 at the junction of the passage 40a with the outwardly flaring, downwardly inclined outlet passage 52. The door 91 is hung on a pin 92 that is pivoted in a recess 93 provided in the housing 40. Normally when coal is being fed by the screw 35 the door 91 will be pushed open by the coal just sufficient to allow it to fall. When the coal feed is shut off the door 91 falls down by its own weight to prevent the radiant heat from the combustion chamber reaching the screw 35. In most installations the door 91 is not necessary.

From the foregoing description it is believed that the construction and advantages of a stoker embodying my invention will be readily apparent to those skilled in this art. Having thus described my invention, what I claim as new and desire to secure by Letters Patent is:

1. A stoker for furnaces comprising a hopper, feed screws in the bottom of the hopper, means to drive said screws, horizontally extending feed screw housing tubes projecting from the hopper for feeding and delivering fuel into the furnace, said tubes being D-shaped in cross section and having outlet openings extending angularly downward from the screw ends, the most forward portion of the top of the outlet openings being about the level of the axis line of the screws, the side walls of said outlet openings diverging to the discharge ends of the openings and the bottom walls of the outlet openings being directed downwardly toward the discharge ends at a greater angle to the horizontal than the top walls of the outlet openings.

2. A stoker for furnaces comprising a hopper, feed screws in the bottom of the hopper, means to drive said screws, horizontally extending feed screw housing tubes projecting from the hopper for feeding and delivering fuel into the furnace, said tubes being D-shaped in cross section and having outlet openings extending angularly downward from the screw ends, the most for-

ward portion of the top of the outlet openings being about the level of the axis line of the screws, the side walls of said outlet openings diverging to the discharge ends of the openings and the bottom walls of the outlet openings being directed downwardly toward the discharge ends at a greater angle to the horizontal than the top walls of the outlet openings, said housing tubes being substantially larger in vertical depth than the diameter of the screws therein.

3. A stoker for furnaces comprising a hopper, feed screws in the bottom of the hopper, means to drive said screws, horizontally extending feed screw housing tubes projecting from the hopper for feeding and delivering fuel into the furnace, said tubes being D-shaped in cross section and having outwardly flaring outlet openings extending angularly downward from the screw ends, the most forward portion of the top of the outlet openings being about the level of the axis line of the screws, and the side and bottom walls of said outlet openings flaring outwardly and downwardly, said tubes having integral rectangular portions below the outlet ends thereof adapted to support the outlet ends of the tubes, and air nozzles extending through said rectangular portions and terminating at the lower edges of the bottom walls of said outlet openings.

4. A stoker for furnaces comprising a hopper, feed screws in the bottom of the hopper, means to drive said screws, horizontally extending feed screw housing tubes projecting from the hopper for feeding and delivering fuel into the furnace, said tubes being D-shaped in cross section and having outwardly flaring outlet openings extending angularly downward from the screw ends, said tubes also having integral hollow supports below the outlet ends thereof supporting the outlet ends of the tubes, a blast plate extending through each hollow support and removably mounted therein below the outlet end of the tube, and an air nozzle extending into each hollow support over the blast plate.

5. A stoker for furnaces, comprising a hopper, feed screws extending across the bottom of the hopper, drive means at one side of the hopper to which said screws are attached, and feed screw housings mounted on the opposite side of the hopper and extending from it, said housings having substantially D-shaped passages therein substantially larger than the feed screw diameters and said feed screws extending into said passages and resting on the floors thereof, the said housings having angularly, downwardly directed outer ends that expand from the ends of the feed screws outwardly, the roofs of the housing passages at the extreme outer ends thereof being at least as high as the screw axes.

GEORGE A. KOHOUT.
